(57) **CLAIM**

The ornamental design for a device dock, as shown and described.

DESCRIPTION

FIG. 1 is a top, front perspective view of a device dock showing my new design;

FIG. 2 is a bottom perspective view thereof;

FIG. 3 is a top plan view thereof;

FIG. 4 is a front elevation view thereof;

FIG. 5 is a left side elevation view thereof;

FIG. 6 is a right side elevation view thereof;

FIG. 7 is a back elevation view thereof; and,

FIG. 8 is a bottom plan view thereof.

The broken line in the figure drawings represents unclaimed environment only and forms no part of the claimed design.
